(57) **CLAIM**

We claim the ornamental design for a terminator bracket, as shown and described.

DESCRIPTION

FIG. 1 is a side elevation view of a terminator bracket of the present design.

FIG. 2 is an end elevation view of the terminator bracket as viewed from the left side of FIG. 1.

FIG. 3 is a top plan view of the terminator bracket shown in FIG. 1.

FIG. 4 is an end elevation view of the terminator bracket as viewed from the right side of FIG. 1.

FIG. 5 is a side elevation view of the terminator bracket taken from the side opposite that of FIG. 1; and,

FIG. 6 is a bottom plan view of the of the terminator bracket.
